[57] CLAIM

The ornamental design for a condom package, as shown and described.

DESCRIPTION

FIG. 1 is a perspective view of a condom package showing my new design using two folds;

FIG. 2 is a perspective view of the condom package of FIG. 1, shown in partial folded condition;

FIG. 3 is a perspective view of the condom package of FIG. 1, shown in partial folded condition similar to FIG. 2 and with a side flap folded in;

FIG. 4 is a plan view of the condom package of FIG. 1, shown in completely unfolded condition;

FIG. 5 is a plan view of the condom package of FIG. 1, similar to FIG. 4, but with the bottom tabs folded in;

FIG. 6 is a perspective view of a second embodiment of FIG. 1 shown in partial folded condition similar to FIG. 2;

FIG. 7 is a perspective view of a third embodiment of FIG. 1 shown in partial folded condition similar to FIG. 2;

FIG. 8 is a perspective view of a fourth embodiment of FIG. 1 shown in partial folded condition similar to FIG. 2;

FIG. 9 is a perspective view of the fifth embodiment of FIG. 1 shown in partial folded condition similar to FIG. 2;

FIG. 10 is a perspective view of a sixth embodiment of FIG. 1 shown in partial folded condition similar to FIG. 2;

FIG. 11 is a perspective view of a seventh embodiment of a condom package showing my new design using one fold;

FIG. 12 is a perspective view of the condom package of FIG. 11 shown in partial folded condition similar to FIG. 2;

FIG. 13 is a plan view of the condom package of FIG. 11 shown in completely unfolded condition;

FIG. 14 is a perspective view of an eighth embodiment of a condom package showing my new design using three folds;

FIG. 15 is a perspective view of the condom package of FIG. 14 shown in partial folded condition similar to FIG. 2; and,

FIG. 16 is a plan view of the condom package of FIG. 14 shown in completely unfolded position.

The corresponding panel layout and slot types of FIG. 6 through 10 inclusive may be provided on the one or three fold designs of FIGS. 11, 14.

In the figures, dashed lines represent condom wrappers, visible environmental structure which may be inserted into slots of the package once the package is folded.
